CLAIM

The ornamental design for telephone set with integral, unitary telephone handset and base therefor, as shown and described.

DESCRIPTION

FIG. 1 is a top plan view of the base for a telephone set, and a bottom plan view of the handset for a telephone set showing my new design in spaced apart relationship; FIG. 2 is a top plan view of the telephone set in cradled relationship;

FIGS. 3 and 4 are respectively front and rear elevational views thereof;

FIGS. 5 and 6 are opposite side elevational views thereof; and

FIG. 7 is a bottom plan view of the telephone set.
